[57]

ABSTRACT

A combination lock for engine starters in which a combination of digits must be successively entered at a keyboard to move a locking member having a pawl through a number of positions in which the pawl interferes with the closing of the engine's starter solenoid to one position in which the pawl does not so interfere, and the locking member being normally spring urged toward an interfering position of the pawl to which the pawl is returned after the solenoid has been successfully closed, or as a result of the entry of an erroneous combination.

COMBINATION LOCK FOR ENGINE STARTERS

FIELD OF INVENTION

This invention relates to locking means to control the use of a vehicle having an engine, and to prevent use of it by unauthorized persons or prevent use of it by a person whose coordination or manual dexterity is impaired, for instance, by intoxication, drug use, or emotional upset. More particularly, the invention relates to a novel combination lock for the engine starter system which can be unlocked by keyboard insertion of a multiple digit number in a certain sequence without error during insertion.

BACKGROUND AND PRIOR ART

Because of the heavy loss of life on the highways in recent years there has been an increased effort to prevent persons from driving vehicles who are not in full control of their faculties, and there have been devices suggested for preventing a vehicle from being driven by a person unless he can perform a predetermined series of functions as a condition precedent to driving the vehicle. Some such systems require the errorless entry of a permutation of numbers into a keyboard within the vehicle prior to starting it, and the present invention is of this latter type.

THE INVENTION

This disclosure teaches a mechanism in which the starter solenoid of the engine is modified and several parts added thereto, so that a pawl riding in a slot in the solenoid plunger is normally spring urged to a position in the slot in which the pawl prevents the solenoid plunger from responding when the solenoid winding is energized. A stepping motor is used to change the position of the pawl in the slot to a position permitting the solenoid plunger to close, but only if the stepping motor is stepped through multiple positions without any error. Otherwise, the spring immediately returns the pawl to the disabling position and the expectant-driver is defeated. Individual push-button electric switches on the keyboard are used to energize the steps of the stepping motor, and the sequence in which they are depressed determines the succession of steps through which the stepping motor is actuated by a person trying to move the pawl to the solenoid-enabling position. The structure of the stepping motor is such that its armature can advance only one incremental step at a time when a new step actuator winding is energized, so that if the person pushes the buttons in the wrong sequence, the error will release the armature to be returned to its initial position by the spring.

It is a major object of this invention to provide an engine starter lock wherein the steps which actually occur in response to the keyboard entry of a series of digits comprise mechanical movements of parts which are located at and within the solenoid, the latter being inaccessibly located under the hood, generally in the vicinity of the starter motor, and out of sight to thwart efforts to defeat the lock by a person trying to observe the positions of parts or by adding jumpers to the wiring. In some prior art systems, especially where the sequence is decoded by electrical circuitry at the push buttons, the system can be defeated if the wire coming from it can be identified. In the present lock, there are a number of wires coming from the push button unit,

but access to them is of no help to the unauthorized person, since only the stepping motor can decode their energization sequence.

Another major object is to provide a lock in which the mechanism is immediately reset to an initial dormant condition whenever an error is made in the sequence, or else as soon as the starter motor has been operated.

A further object is to provide a lock in which the numerical combination of digits which must be entered, as well as their sequence, can be easily varied to change both the required combination, and the degree of difficulty involved in successfully enabling the starter. It is possible to use the same number several times in a sequence or to vary the total number of digits which must be entered. Consequently, there are thousands of possible combinations. Moreover, as discussed in a later portion of this specification, the lock is tricky to operate. Because of the spring constantly seeking to reset the lock to its initial state, the operator must hold the push button which was most recently pressed until after he has pressed the next one in the sequence. If not the spring will reset the mechanism before he presses the next button and while the stepping motor is unenergized. Thus, more than one finger at a time must be used on the push buttons. The operation of the lock could be simplified by adding mechanical or electrical means for automatically keeping the last step energized while the next is taken, if easier access is required.

Still a further object of the invention is to provide a lock which uses many of the parts already in a vehicle starter system, with only minor modifications, thereby holding down its initial cost.

Another object is to provide a starter lock equally adaptable either to Diesel or to spark fired engines. Other objects and advantages of the present invention will become apparent during the following discussion of the drawings, wherein:

DESCRIPTION OF DRAWINGS

FIG. 1 is a view illustrating a starter lock assembly according to the present invention mounted in an automobile;

FIG. 2 is a front view of the keyboard assembly showing the various push buttons carried thereby;

FIG. 3 is a cross-sectional view through a conventional starter motor and solenoid showing features of the present invention added thereto;

FIG. 4 is an enlarged cross-sectional view through a stepping motor which forms part of the present assembly;

FIG. 5 is a detail perspective view showing the armature of the stepping motor.

FIG. 6 is an electrical wiring diagram of the lock system;

FIG. 7 is an enlarged perspective view showing the starter solenoid plunger and the plunger-locking member surrounding it;

FIG. 8 is a partial sectional view taken along line 8-8 of FIG. 3 and showing the starter motor plunger with the locking member surrounding it and geared for control by the stepping motor; and

FIG. 9 is an enlarged partial cross-sectional view taken along line 9-9 of FIG. 7.

Referring now to the figures of the drawing and especially to FIG. 1, this view shows an automotive vehicle V having an engine E including a starter motor M. The

starter motor M is also seen in FIG. 3 and includes a solenoid arrangement S which is attached to the starter motor and forms a part thereof in standard automotive equipment, but which has been somewhat modified as set forth below for present purposes. In FIG. 1, the vehicle V is also shown to include a keyboard assembly K which is connected by a series of wires to parts which are attached to the solenoid S in the manner to be described herein below. The keyboard K has push buttons 1, 2, 3, 4, and 5 comprising parts of the switches 1, 2, 3, 4, and 5 as illustrated in the wiring diagram of FIG. 6, and the keyboard also includes a START push button 6 corresponding with the switch labelled 6 in FIG. 6. The switches 1 through 6 inclusive are all normally open and are closed when their push buttons are depressed.

Referring now to FIGS. 3, 7, and 8 the solenoid S includes a plunger P which is drawn to the left in FIG. 3 when the windings W of the solenoid are energized by applying electrical power to the terminal T. The coil spring C in the standard solenoid urges it to the right when the winding W is not energized and this also normally maintains the contacts of the electrical switch open, these contacts being labelled A and B in FIGS. 3 and 6. When the plunger P is pulled to the left by the energizing of solenoid windings W, the lever L is also pulled to the left about its pivot and this engages the starter gear G with the engine fly wheel teeth (not shown) in a manner well known per se, while current through the contacts A and B causes the starter motor M to rotate. All of this is of course very well known in the prior art relating to engine starters.

It is the purpose of the present locking system to prevent the plunger P in the solenoid S from being pulled leftwardly even though the windings W in the solenoid may be momentarily energized. For this purpose, I have altered the plunger P by milling a T-shaped slot 10, 12 into the outer surface of the plunger, this slot including a longitudinal slot portion 10 joining with a circumferential slot portion 12 as can be seen in FIGS. 7 and 8. In addition, I have further altered the ordinary starter solenoid assembly by putting a guide plate 14 around the plunger, which guide plate lies against the right-hand end of the solenoid winding assembly W and serves as an abutment for the left end of the compressed coil spring C. The inner periphery 14a of the guide plate 14 is large enough so that the plunger is free to slide through it, and the two outwardly extending legs of the guide plate 14 are separated by a distance great enough to receive a locking ring member 16 as can best be seen in FIGS. 7, 8, and 9. The ring 16 has a pawl 18 which extends inwardly from its inner periphery through an opening in the guide plate 14 and into the T-shaped slot 10, 12. Thus, the coil spring C presses against one leg of the guide plate 14 which in turn is supported against its other leg by the end of the winding assembly W of the solenoid and therefore the spring C does not bind the rotation of the ring 16 located between the legs 14. The other end of the coil spring C lies against an abutment D which is fixed to the plunger.

By an inspection of FIGS. 7 and 8 it should become apparent that the plunger P cannot be pulled to the left by energizing of the winding W of the solenoid S unless the pawl 18 is in alignment with the longitudinal slot 10. Thus, there is only one annular position of the ring 16 in which the plunger P can be pulled to the left by

the winding W of the solenoid. A tension spring 20 as shown in FIGS. 7 and 8 is attached at one end to the housing H of the solenoid S, and the other end of the spring 20 is attached to a pin 21 which extends outwardly from the ring 16. As a result, the spring 20 attempts to rotate the ring clockwise as shown in FIGS. 7 and 8 unless this rotational effort is successfully opposed by the gearing 24 and 26 shown in FIG. 8. The spring 20 normally holds the ring 16 in such a position that the pawl 18 is to one side of the circumferential slot 12 and therefore out of alignment with the longitudinal slot 10 as shown both in FIGS. 7 and 8. The gear 26 on the stepping motor 22 as shown in FIGS. 4 and 8 is connected by an idler gear 24 to the teeth 16a in the outer periphery of the ring 16. These teeth do not go all the way around the ring 16, but extend merely through a sector thereof sufficient that the stepping motor can move the pawl 18 back and forth in the slot 12. The stepping motor 22 is bolted to the housing H by screws 28, and the housing H has a small opening in its side through which the idler gear 24 can engage the teeth 16a of the ring 16. The spring 20 is strong enough that when the stepping motor 22 is not energized at the proper one of its windings, the spring can drag the ring 16 and the gears 24 and 26 around to return the stepping motor 22 to a locking position in which the pawl 18 is located, as shown in FIGS. 7 and 8, in the transverse slot 12, out of alignment with longitudinal slot 10. The plunger P is further provided with a keyway slot 30 along its side diametrically opposite the slot 10, and a key 32 is inserted in the slot 30 and into a portion of the wall of the opening in which the plunger slides within the solenoid assembly so as to prevent the plunger from rotating, thereby maintaining the longitudinal slot 10 always in the same position with respect to the position of the gearing 24 and 26.

The construction of the stepping motor 22 can best be seen in FIGS. 4, 5 and 6. The stepping motor is mounted in its own housing 34 and has suitable bearings for receiving the shaft 36. Within the stepping motor housing 34 there are located a series of spaced actuator coils, such as the coils 38 and 40 which are shown as being among a multiplicity of such actuator coils evenly spaced around the stepping motor. As can best be seen in FIG. 6 the coils are equally spaced and are all connected at one terminal to the vehicle's source of electrical power through the ignition key switch F, while the other ends of the five actuator coils including the coils 38 and 40 are respectively connected to the switches 1 through 5 inclusive of the starter keyboard K. It should be noted that the coils would not be sequentially connected to the switches 1 through 5 in a practical installation. Thus, a person not knowing the correct combination would not know the sequence in which to press the push buttons on the keyboard K in order to successfully actuate the coils. The effect of actuating the coils is to pull the armature 42 around inside the housing 34 of the stepping motor 22, thereby rotating the shaft 36 to which the armature 42 is connected, thereby also to rotate the ring 16. It should be especially noticed that the armature 42 is very narrow and therefore cannot be attracted to just any position by the energizing of just any one of the actuator coils. Because of the narrowness of the armature 42 as measured in the circumferential direction of the stepping motor, the armature can be attracted only to the next adjacent position by opening one of the

switches 1 through 5 and closing another one of them. If an attempt is made to attract the armature through too great a distance circumferentially, the result will be the same as de-energizing the stepping motor because the spring 20 will return the ring 16 to its initial position as shown in FIGS. 7 and 8 in which the pawl 18 is out of alignment with the slot 10. Moreover, it is possible to rotate the armature 42 too far, with the result that the pawl 18 goes beyond longitudinal slot 10 and into the portion of the circumferential slot 12 lying beyond it, whereby the solenoid S when energized still cannot attract the plunger P to the engine starting position.

The procedure required for starting the engine can best be explained with reference to the electrical diagram of FIG. 6. When the operator of the vehicle inserts the key into the ignition switch F and closes the switch, the common terminal of all the actuator coils of the stepping motor 22 will be energized, the vehicle ignition coil (not shown) will be energized, and one side of each of the keyboard switches 1 through 6 will be energized. At this time, the operator of the vehicle will press whichever one of the keys 1 through 5 is operative attracting the armature 42 within the stepping motor 22 to the first step position from its rest position as established by the tension of the spring 20. Then, he will depress the second button operating to attract the armature 42 to the second step position, whereupon he will release the first push button and the armature will then move to the second position pulling the spring 20 against it by rotating the ring 16. The operator then proceeds through whatever other positions are required to accomplish the entire keyboard insertion of the combination, the operator on each occasion pressing the push button required to move the armature from whatever position it is presently in to the next adjacent position before he releases the button which he has been holding. When at last he has entered the entire combination, he continues to hold the last push button in the pressed position while he presses the START push button 6 to energize the winding W of the solenoid, which then closes the switch A, B, and engages the starter motor gear G.

If the operator has inserted the correct combination, the pawl 18 will be aligned with the longitudinal slot 10. Therefore the plunger will be able to close when he pushes the START switch 6. Conversely, if the operator has entered an incorrect combination, the pawl 18 will either be located in the wrong portion of the circumferential slot 12 or will have returned to the initial position shown in FIGS. 7 and 8 when the operator tries to make the stepping motor take too large a step, whereby the stepping motor loses control and the spring 20 returns the ring 16 to its initial position. In either event, the operator will then have to start all over again entering the combination.

As set forth in the objects of the invention, one of the particular advantages of the present lock is that the decoding of the combination is accomplished at the starter motor inside of the solenoid housing at a location where it is impossible for anyone to see whether or not the pawl 18 has been moved into alignment with the longitudinal slot 10. Hence, it is virtually impossible to defeat the lock by observing what happens when various ones of the push buttons 1 through 5 are depressed.

Although in the present illustrative embodiment five push buttons and five windings have been shown and

described, it is to be understood that a larger number thereof can be employed if desired in order to make the operation of the lock more difficult. In particular, it might be desirable to use ten push buttons instead of 5 only five, and have some of the push buttons connected to nothing so that a person has a larger choice of incorrect combinations. Using this approach, when a person presses a non-connected push button, it would result in complete release of the stepping motor to return the 10 lock to its initial inoperative position.

The present invention is not to be limited to the specific embodiment illustrated in the drawings, for obviously changes in the lock can be made within the scope of the attached claims.

I claim:

1. A combination lock for a vehicle engine having a starter mechanism including a starter solenoid having a reciprocable plunger adapted to be drawn from an initial rest position to an engine-starting position when the solenoid winding is energized, the lock comprising:
  - a. a locking member supported by the starter solenoid and including a pawl, the member being moveable through multiple possible positions wherein the pawl interferes with reciprocation of the plunger into starting position and said multiple positions including one intermediate position in which the pawl frees the plunger to move into starting position;
  - b. spring means operative to bias the locking member and pawl away from said one position;
  - c. motor means operative to move through steps and coupled to move the locking member pawl through said multiple positions including said intermediate position, the motor means including an actuator coil for each step capable when energized of moving the motor means into the corresponding position, and the motor means having its position determined by said spring means when none of its coils is energized; and
  - d. keyboard means having multiple push buttons at least some of which are connected to energize the various motor coils, and the vehicle including means to energize the starter solenoid.

2. The combination lock as set forth in claim 1, wherein said solenoid comprises a housing containing said plunger, and said plunger has a longitudinal slot extending longitudinally along its side, and said locking member comprising a ring mounted for rotation on said housing and surrounding said plunger, the pawl being fixed to the ring and moveable with rotation of the latter into said multiple possible positions, in one of which the pawl is in alignment with the slot.

3. The combination lock as set forth in claim 2, wherein the slot is T-shaped and the longitudinal slot joins a circumferential slot located to receive the pawl when the solenoid is de-energized.

4. The combination lock as set forth in claim 3, wherein the spring means is coupled between the housing and the ring, and normally urges the ring into a rotational position in which the pawl is in the circumferential slot of the plunger, out of alignment with its longitudinal slot.

5. The combination lock as set forth in claim 2, wherein said ring having gear teeth on its outer periphery and the housing having an opening in it opposite said teeth, and the motor having a shaft coupled to said ring by gear means meshing with said teeth.

6. The combination as set forth in claim 5, wherein said motor means including an armature mounted on said shaft, and said actuator coils being mounted in successive annular positions around said shaft, the coils and the armature being placed and shaped such that a newly energized coil can attract the armature to step to it only if the armature is already at an immediately adjacent position.

7. The combination as set forth in claim 6, wherein

the returning force of the spring relative to the torque of the motor means is such that when one coil is energized and a push button is erroneously pressed energizing a non-adjacent coil, upon de-energizing of said one coil, the spring means will return the ring to an interfering position in which the pawl is out of alignment with the slot.
